UNITED STATES PATENT OFFICE.

GEORGE A. HULL, OF CHICAGO, ILLINOIS, ASSIGNOR TO EQUIPMENT SPECIALTIES CO., OF CHICAGO, ILLINOIS, A CORPORATION OF ILLINOIS.

VENTILATING DOOR FOR THE HATCHWAYS OF REFRIGERATOR CARS.

Application filed December 11, 1924. Serial No. 755,203.

In the operation of railroad refrigerator cars it is customary practice in chilly or cold weather to dispense with ice in the ice compartment and to raise the hatchway covers leading to these ice compartments so that cold air can permeate around the perishable commodities and so that the breeze resulting from the motion of the car can blow down through the hatchways into the car. 10 The car is then said to be travelling "under ventilation."

These open hatchways are an invitation to tramps to crawl down into the ice compartment and pilfer fruits or other commodities packed in the car. This is made possible because the bulk head which separates each ice compartment from the main compartment has openings at top and bottom for the circulation of cold air, and 20 these openings frequently afford accessibility to the commodities packed in the main compartment.

Theft-proof ventilating doors have heretofore been provided for these hatchways having spaced cross bars or other open-work construction to permit of a free circulation of air through the car, but the prior ventilating doors have generally been objectionable for numerous reasons. One objection is that 25 when these doors are in open position they have to occupy space in the main compartment and hence they are apt to be jammed or injured in the packing of the main compartment. Also, because of the fact that 30 they have to slide into the main compartment, their movement into open position is often obstructed by the end of the door striking fruit crates or part of the cargo in the main compartment. These prior doors have 35 been locked in closed position from a point inside the main compartment, and, consequently, if it is desired to insert ice in the ice compartment as a result of change of temperature in transit, access cannot be had 40 to the point of locking for opening the door without first removing a considerable part of the cargo in the end of the car. These doors are also frequently injured by the packing 45 of ice into the ice compartment.

I have obviated these objections by providing a theft-proof ventilating door for hatchways which does not have to occupy space in the main compartment. According to the present invention, the doors of 50 both hatchways move into the intervening

space between said hatchways when the doors are moved to their open position. This space may be defined as that area between vertical planes passing through the upper inner edges of both hatchways. This practice avoids movement of the door into the main compartment and still accommodates a door of ample size to close the entire hatchway. Such disposition of the door in its open position also protects the same 60 against jamming or other injury incident to the packing of ice into the ice compartment. The present door can also be locked or sealed from the open top of the hatchway.

Referring to the accompanying drawings 10 in which I have illustrated a preferred embodiment of my invention:

Figure 1 is a sectional view taken transversely through a refrigerator car in the plane of the ice compartment and hatchways;

Figure 2 is a sectional view taken on the plane of the line 2—2 of Figure 1;

Figure 3 is a detail sectional view, taken approximately on the line 3—3 of Figure 1, 80 illustrating the mounting of the articulated door in the guide channels;

Figure 4 is a longitudinal sectional view through a door of modified design;

Figure 5 is a transverse detail section 85 thereof, taken on the plane of the line 5—5 of Figure 4.

Figure 6 is a fragmentary view on a plane similar to Figure 1 showing a different arrangement of paths for the hatchway doors, 90 and

Figure 7 is another transverse sectional view through a refrigerator car showing another arrangement of the doors.

Referring to Figures 1 and 2, the upper portion of a typical refrigerator car is illustrated by the side wall 11, the end wall 12, and the roof 13. The side and end walls are of the usual heat insulating construction embodying several layers of hair felt with 95 one or more air spaces intervening, no specific description of these details being necessary as they are points of construction well known in the art.

The ice compartment 10 is defined at each 105 end of the car between the end wall 12 and an adjacent bulk head 14. The loading of this ice compartment is effected through two hatchways 15, disposed on opposite sides of the central running board 16 which 110

extends along the top of the car. It is through these hatchways that the cold air is circulated when the car is travelling under ventilation, and which it is desirable to protect by ventilating doors.

These hatchways are defined between two transverse headers 17 and 18 extending from side to side of the car for supporting the roof thereof. Said headers may form the front and rear sides of the hatchways, or may have plates 19 and 21 secured thereto defining these hatchway walls. The inner and outer side walls of each hatchway are formed by longitudinal plates or boards 22 and 23 extending between the transverse plates 19 and 21. The four plates defining each hatchway preferably project above the roof 13 to raise the upper edge of the hatchway opening. The upper inner faces of these hatchways are preferably bevelled at a slight angle, as indicated at 24, to make a tight fit with the plugs or covers 25. The lower portions of the end and outer walls of each hatchway below the bevelled portions 24 may be extended down substantially vertically. The inner walls of the hatchways are preferably lined with sheet metal 26 as a protection against injury from ice in the packing of the ice compartment.

In describing one of the preferred embodiments of my invention, mention should first be made of the fact that this embodiment utilizes a unique structural feature in refrigerator car construction which has been made the subject of United States Letters Patent No. 1,220,830, issued to William H. Emerick. This improved feature consists in flaring the inner side walls of both hatchways downwardly toward each other, as indicated at 28-28. These flaring side walls are co-extensive with the inner side plates 22-22 and form an intervening wall of wedge-shaped section between the two hatchways. The provision of these enlarged openings at the lower portions of the hatchways facilitates the chopping in of the ice and the distribution of it toward the intermediate portion of the ice compartment. It also affords a freer escape for a rising column of warm air when the car is traveling under ventilation. I utilize the space defined between these two sloping walls 28-28 for receiving and housing the ventilating doors of both hatchways when the latter are moved to their open positions. Moreover, I utilize the considerable length of each sloping wall 28 in forming a long inclined runway or chute into which the ventilating door is slid when it is moved to its open position. The inclination of the wall 28, which is the salient feature of the above-mentioned patent, is of great advantage in the present situation because the door does not have to pass through any considerable angle in being moved between its open and closed positions.

Both walls 28 are preferably constructed of sheet metal, either in the form of separate sheets or in the form of a single sheet folded in V-form, to extend up both sides of the wedge-shaped dividing wall. These sheet metal walls 28 are spaced from inner walls 29 constructed of wood header plates or boards extending between the transverse headers 17 and 18 and pointing down to an apex similar to the walls 28-28. Transverse struts 31 are secured to the sloping inner walls 29 for bracing the same.

The door is indicated at 32, and is of articulated construction so that it can move through the angle incident between its open and closed positions. This door slides in channel guides 33 which are secured to the end walls of the hatchways, as by screws or bolts. Each channel guide has a lower inclined portion extending substantially parallel with the wall 29, but spaced therefrom, and an upper portion which extends across the front and rear sides of the hatchway, preferably along the bottom of the bevel 24. The two portions of each channel guide are joined by a gradual curve 33', through which the articulated door can be moved without difficulty.

The door is constructed of a series of spaced cross bars 35 of angle section connected at their ends by links 36. As shown in Figure 3, the lower flange of each cross bar is turned up at the end, as indicated at 37, to provide an attaching flange to which the links 36 can be connected. The pivotal connections between adjacent links 36 may occur intermediate the cross bars 35, as indicated at 38 in Figure 1; or the ends of adjoining links may be overlapped and pivoted to the end attaching flanges 37 of the cross bars.

The door is adapted to be locked or sealed in its closed position through hinged locking angles 41 which are pivoted to brackets 42 secured to the front and rear walls of each hatchway. These locking angles are adapted to be swung down behind the vertical flange of the foremost cross bar 35, the angle 41 and the cross bar having cooperating apertures for receiving the hasp of a padlock or a lead seal. It will be noted that the front edge of the door need not be carried into abutting contact with the side wall 23 of the hatchway; being carried only to a point where the intervening space will not greatly exceed the spacing between the cross bars 35. This also applies to the rear edge of the door. This shortens the necessary length of the door.

The sloping walls 28 may be secured in spaced relation to the walls 29 in any suitable manner to form the necessary inclined chutes or runways for receiving the doors when moved into their open positions. A preferred expedient is illustrated in Figure

3, where it will be seen that the lateral margins of these walls or plates 28 are secured to the lower flanges of the guide channels 33. The upper edges of these sheet metal plates 5 are preferably turned back, as indicated at 44, to form rounded upper edges at the entrance of each chute. These entrances are normally closed by small flaps 45 which are hinged to plates 46 secured to the hatchway 10 walls 22. These hinged flaps lie substantially in the vertical plane of these inner hatchway walls 22 where they will not be injured in the packing of ice into the ice compartment, and where they will prevent 15 any of this ice from falling into the chutes.

In Figures 4 and 5 I have illustrated a modified construction of articulated door for movement in the preceding arrangement of the guides or in any analogous arrangement of guides. In this form the cross bars also consist of angle bars. The ends of the upright flanges of these angle bars are provided with apertures through which are threaded flexible cables 48. The cross bars are maintained in spaced relation by a series of short spacing sleeves 49 threaded on these connecting cables between adjacent cross bars. These spacing sleeves 49 are sufficiently short, and sufficient clearance is maintained between them, to provide a very flexible connecting means between the cross bars. If desired, the cross bars or spacing sleeves may be fixedly attached to the connecting cables at spaced intervals to prevent the cross bars and sleeves from bunching together at either end of the door. This may be accomplished by providing certain of the spacing sleeves with threaded bosses 51 for receiving set screws 52 which press clamping blocks 53 up against the connecting cable 48.

In Figure 6 I have illustrated a modified construction, departing from that previously described in that the channel guides for the doors are curved upwardly to give the requisite length of guide for receiving each door, instead of being carried down to the apex point shown in Figure 1. In this arrangement, the channel guides 33 are curved upwardly in back of the inner walls 29 through a gradual curve. This permits the wedge-shaped dividing wall between the hatchways to be cut off in frustum section.

55 Figure 7 illustrates a modification in
 which the two ventilating doors move in
 rectilinear paths. In this construction the
 doors may be of rigid assembly comprising
 side channels or angles 56 connected by
 transverse angle bars 57. The guide chan-
 nels 58 extend horizontally in a substantial-
 ly straight line across the hatchways and
 through openings 59 in the inner walls 22'
 of the hatchways. The two guide channels
 60 58 are offset vertically so that both hatch-
 way doors can be slid into the same vertical
 65

space defined between the walls 22'. When in their open positions, the front angle bars of these doors close the openings 59 so that the entrance of ice into these guideways is prevented.

This construction may be embodied in that design where the sloping inner walls 28 are employed, or where the inner walls 22' are carried straight down to the bottoms of the hatchways, as illustrated in Figure 7.

The locking or sealing means described in connection with Figure 1 is also applicable to the embodiments shown in Figures 6 and 7, or any other locking or sealing means may be employed.

I do not intend to be limited to the particular details herein shown and described, as it will be obvious that various modifications and rearrangements of parts may be made within the spirit and scope of the invention.

I claim:

1. In combination, a railroad car comprising a roof having a pair of hatchways, and a ventilating door for one of said hatchways movably supported to close said hatchways or to lie wholly between the adjacent edges of said hatchways.

2. In combination, a railroad car comprising a roof having a pair of adjacent transverse hatchways, and slideable ventilating doors for each of said hatchways adapted, when open, to occupy positions between said hatchways.

3. In combination, a railroad car comprising a roof having a pair of adjacent transverse hatchways, a slideable guard for one of said hatchways, and guide means for confining said guard in the space between said hatchways when said guard is in its open position. 100
105

4. In combination, a railroad car comprising a roof having a pair of adjacent transverse hatchways, and a door for one of said hatchways movable into space defined between vertical planes passing through the upper inner edges of said hatchways, and below top of car.

5. In combination, a railroad car comprising a hatchway, and a ventilating door for said hatchway movable into and out of closed position transversely of the car. 115

6. In combination, a railroad car comprising a roof having a pair of hatchways, and 120 ventilating doors for both hatchways movable into and out of closed positions transversely of the car.

7. In combination, a railroad car comprising a roof having a pair of adjacent transverse hatchways, and a ventilating door for one of said hatchways, said door being moved to open position by sliding in a direction generally toward the other hatchway. 125

8. In combination, a railroad car comprising a roof having a pair of hatchways, said

hatchways being spaced a distance less than the aggregate width of both doors, ventilating doors for each of said hatchways, and guideways for each of said doors extending 5 in a direction generally toward the other hatchway.

9. In combination, a railroad car comprising a roof having a hatchway, and an articulated grating for said hatchway movable 10 into and out of operative position transversely of the car.

10. In a railway refrigerator car, the combination of a roof provided with a hatchway, one of the walls of said hatchway having 15 its lower portion sloping obliquely downwardly relative to its upper portion, and a ventilating door for said hatchway movable into a position alongside said sloping wall portion.

20 11. In a railway refrigerator car, the combination of a roof provided with a hatchway, one of the walls of said hatchway having 25 its lower portion sloping downwardly and inclined toward the central plane of the car, a ventilating door for said hatchway, and guide means for said ventilating door extending substantially parallel to said sloping wall portion.

12. In a refrigerator car, the combination 30 of a roof provided with a hatch opening, a frame surrounding said opening and forming the walls thereof, one of said walls having its lower portion sloping obliquely downwardly relative to its upper portion to permit 35 access to the space beneath said roof at the side of said opening, a ventilating door for said hatch opening, and a receiving chute for said door extending behind the sloping portion of said last-mentioned wall.

40 13. In a railway refrigerator car, the combination of a roof provided with a hatchway, one of the walls of said hatchway having 45 its lower portion sloping obliquely downwardly relative to its upper portion, and an articulated grating for closing said hatchway adapted in its open position to occupy a position substantially parallel with said sloping wall portion.

50 14. In a railway refrigerator car, the combination of a roof provided with a pair of hatchways, the inner walls of both hatchways having their lower portions sloping obliquely downwardly relative to their upper

portions, and ventilating doors for both hatchways movable down along the sloping 55 portions of said inner walls.

15. In a railway refrigerator car, the combination of a roof provided with a hatchway, one of the walls of said hatchway having 60 its lower portion sloping obliquely 60 downwardly relative to its upper portion, a ventilating door for said hatchway, and guide means for directing said door down along the sloping portion of said wall when being moved to its open positon. 65

16. In combination, a railroad car comprising a roof having a hatchway, and an articulated grating for said hatchway comprising a plurality of cross bars pivotally joined by connecting links. 70

17. In combination, a railroad car comprising a roof having a hatchway, guide channels having portions extending cross-wise of said hatchway and portions extending at an angle thereto, and an articulated 75 door for movement in said guide channels comprising a plurality of cross bars and links pivotally connecting the ends of said cross bars.

18. In a railway refrigerator car, a roof 80 having a pair of hatchways, and frames surrounding each of said hatchways, the adjacent walls of the two frames being sloped downwardly towards each other and terminating in a pointed apex to permit ready 85 access to all of the space beneath the roof between the hatchways.

19. In a railway refrigerator car, the combination of a roof provided with a pair of hatchways, a frame surrounding each hatchway and forming the walls thereof, the two inner walls of said two frames being inclined downwardly towards each other and terminating in a pointed apex disposed centrally between said hatchways. 90 95

20. In a railway refrigerator car, an outside enclosing surface having a plurality of openings spaced a distance less than the width of an opening, closure means preventing access to the interior of said car through 100 said openings but permitting passage of air, said closure means being slidable to open the same into a space between said openings.

In witness whereof, I hereunto subscribe my name this 9th day of December, 1924.

GEORGE A. HULL.
